UNITED STATES PATENT OFFICE.

WILLIAM G. KENDALL, OF NEWARK, NEW JERSEY.

SPOUT FOR RECEPTACLES.

1,213,500.

Specification of Letters Patent. Patented Jan. 23, 1917.

Application filed July 13, 1915. Serial No. 39,692.

To all whom it may concern:

Be it known that I, WILLIAM G. KENDALL, a citizen of the United States, residing at Newark, in the county of Essex and State of New Jersey, have invented certain new and useful Improvements in Spouts for Receptacles, of which the following is a specification.

My present invention relates to new and useful improvements in spouts for receptacles, the primary object of my invention being the provision of a spout and closure cap structure which may be constructed for use upon receptacles of various characters and which may be applied to receptacles without the necessity of any threaded connection between the cap, spout and receptacle.

A further object of my invention consists in providing a spout structure of the above described character including an inner closure cap carrying a spout which is extensible from or retractable into the receptacle and an outer closure cap applicable to the first cap and to the spout when the latter is retracted to seal both the inner cap and the spout.

A still further object of my invention is to so arrange the engaging portions of the inner cap and spout that when the latter is in extended position, it will be securely held against any likelihood of displacement.

With these and other objects in view, my invention will be more fully described, illustrated in the accompanying drawings, and then specifically pointed out in the claims which are attached to and form a part of this application.

In the drawings, Figure 1 is a perspective view of my improved spout structure applied to a conventional form of oil can, a portion of the can being broken away to show the construction of its flexible bottom; Fig. 2 is a fragmentary, central vertical sectional view taken through the top of the can, and the closure caps showing the spout in retracted position; Fig. 3 is a corresponding view taken through the top of the can and inner closure cap and through the spout which in this figure is in extended position.

Corresponding and like parts are referred to in the following description and indicated in all the views of the drawings by the same reference characters.

Although I do not wish in any way to limit myself to the application of my spout

mechanism to oil cans of the type disclosed, it being applicable to receptacles of various characters, I have, for the sake of clearness, illustrated it in connection with an oil can having a cylindrical body 10, the bottom 11 of which is formed of relatively resilient or flexible sheet metal provided with a peripheral bead 12 to permit ready buckling of the bottom, under pressure, whereby flow of oil or other liquid from the can may be facilitated. The top 13 of the can is provided centrally with the usual discharge opening surrounded by a downwardly depending annular flange 14 terminating at its lower end in an inwardly directed stop shoulder 15. This flange is preferably of somewhat less internal diameter adjacent its lower end than at its upper end to properly engage the inner closure cap 16, which cap forms a portion of my present invention. This inner cap 16 includes a body portion 17 having an upstanding peripheral flange 18 terminating at its upper edge in an outwardly and laterally directed annular stop shoulder 19. This inner closure is so proportioned that its annular flange 18 will frictionally engage the flange 14 of the can top when the inner closure is forced into the position shown in Fig. 2 with its body portion resting upon the shoulder 15 and its stop shoulder 19 engaging the upper face of the top of the can. The inner closure 16 is formed centrally with a downwardly directed flaring annular flange 20 terminating at its lower end in an outwardly and laterally directed peripheral stop shoulder 21, the closure being formed with an opening defined within the flange 20.

Cooperating with the above described inner closure, is a spout 22 preferably in the form of a tapered seamless tube, the larger end of which extends into the can through the flange 20. This tube, adjacent its outer smaller end, carries a disk 23 which serves as a stop to limit the inward movement of the spout, the disk being so proportioned as to engage the upper face of the body portion of the inner closure with the upper end of the spout spaced somewhat above such portion of the closure. The spout 22, at its lower end, carries a thimble portion 24 which tapers from its lower to its upper end to frictionally seat within the flange 20 of the inner closure when the spout is drawn to its lower edge in an outwardly directed

peripheral stop shoulder 25 adapted to engage against the stop shoulder 21 of the inner closure when the spout is extended. The outer face of the thimble 24 is lightly 5 scored, corrugated or otherwise roughened, as shown at 26, to insure close frictional engagement between it and the inner face of the flange 20 and at the same time not permit leakage of liquid from the can between 10 the thimble and flange. Furthermore, the interengagement of the stop shoulders 21 and 25 will prevent such leakage.

In order to provide means for preventing all escape of liquid from the can 10 when 15 the latter is not in use, I provide an outer closure, indicated as a whole by the numeral 27. This outer closure includes a body portion 28 surrounded by an upstanding peripheral flange 29 tapering from its upper 20 to its lower end and terminating at its free end in an outwardly directed annular stop shoulder 30. This outer closure is formed with a central opening 31 in order that the spout may project through it when it is applied to the inner closure and the outer closure is so proportioned that when its body portion engages the upper face of the stop disk 23 of the spout, its flange will frictionally engage the flange 18 of the inner closure 25 and its shoulder engage the stop shoulder 19 of the inner closure. A cylindrical bonnet 32 surrounds the opening 31 in the body of the outer closure 27, being closed at its upper end and inserted in this bonnet is 30 a packing disk 33 of cork, impregnated paper or other suitable material adapted to receive and seal the upper open end of the spout 22 when the outer closure is forced in place.

40 From the foregoing description, the operation of my improved spout for receptacles will be readily understood and no description of its use is deemed necessary. It should be noted, however, that because of 45 the relatively elongated engagement between the thimble 24 and flange 20 of the inner closure, the spout, when extended, is firmly held against retraction and can be retracted only by considerable pressure exerted directly in axial alignment with the spout. Again, when the spout is in retracted position, all rattling about of the spout within 50 the can is prevented because of the clamping of the stop disk 23 between the inner and outer closures or caps of the receptacle.

Having thus described the invention, what is claimed as new is:

1. The combination with a receptacle including a top having an opening surrounded by a downwardly extending and tapering annular flange terminating in an inwardly directed peripheral stop shoulder, of an inner closure including a body adapted to seat on the shoulder and an upwardly flared annular flange frictionally engaging the flange

of the can top and terminating in an outwardly directed peripheral shoulder engaging the top of the can, said inner closure having a central opening surrounded by a downwardly extending and flaring annular flange terminating in a peripheral stop shoulder, a tubular spout movable through the opening of the inner closure, a stop disk secured to the spout adjacent one end and adapted in one position of the spout to seat 75 upon the upper face of the closure, a frusto-conical tubular thimble secured to the inner end of the spout and terminating at its lower end in an outwardly directed annular flange, said thimble being adapted to frictionally seat in the flared flange of the inner closure with the stop shoulder of the thimble engaging the stop shoulder of the flange, the outer face of the thimble being lightly scored, an outer closure including a 85 body having a central recess adapted to surround the outer end of the spout when the latter is in retracted position and when seated upon the stop disk, an upwardly directed flared annular flange adapted to engage within the flange of the inner closure and terminating in an outwardly directed circumferential stop shoulder engaging the stop shoulder of the inner closure, a closed bonnet surrounding the recess in the outer 95 closure and inclosing the outer end of the spout, and a packing in the bonnet engaging the spout.

2. A combined closure and spout for receptacles including an inner closure having 100 an upwardly directed flared peripheral flange adapted to frictionally engage in the neck of a receptacle and terminating in an annular stop shoulder adapted to engage the upper edge of the receptacle neck, said 105 closure being formed centrally with an opening surrounded by a downwardly extending and flared flange terminating in an outwardly directed stop shoulder, an outer closure including a body adapted to seat 110 in spaced relation to the body of the first closure and formed centrally with a recess in alignment with the opening of the inner closure and peripherally with an upwardly directed and outwardly flared annular 115 flange to engage the flange of the inner closure and terminating in an outwardly directed circumferential stop shoulder to engage the stop shoulder of the inner closure, a bonnet open at its lower end and closed at its upper end secured to the outer 120 face of the outer closure and surrounding the recess therein, a tubular spout provided adjacent its upper end with a stop disk adapted to be clamped between the inner 125 and outer caps when the spout is in retracted position, and a thimble secured to the lower end of the spout and including a frusto-conical body portion adapted for frictional engagement in the downwardly 130

directed flared flange of the inner closure and terminating in an annular stop shoulder engageable against the stop shoulder of said flange of the inner closure.

3. The combination with a receptacle having a neck adapted to receive a frictional closure cap, of an inner frictional closure cap engageable in the neck and formed centrally with a spout receiving opening surrounded by a downwardly directed spout engaging flange, a spout having means at its lower end for engagement in such flange when the spout is extended, means at its upper end to support the spout when retracted, and an outer frictional sealed closure engageable within the first closure and having a bonnet to receive the outer end of the spout.

4. The combination with a receptacle having a circular depressed portion formed

with an opening surrounded by a depending flaring flange, a spout extending through the opening and formed at its inner end with a tapered thimble for engagement within the flange when the spout is projected and adjacent its outer end with an annular stop shoulder, a closure having an upstanding annular flange adapted to frictionally engage the peripheral wall of the depressed portion when the closure is applied and forced into engagement with the stop shoulder of the spout and having a recess for the end of the spout projecting beyond the stop shoulder, a bonnet formed on the closure to surround the extended end of the spout, and a packing in the bonnet to seal the spout.

In testimony whereof I affix my signature.

WILLIAM G. KENDALL. [L.S.]
